UNITED STATES PATENT OFFICE

MARTIN FRISCH, OF ST. LOUIS, MISSOURI, ASSIGNOR TO INTERNATIONAL COMBUSTION ENGINEERING CORPORATION, OF NEW YORK, N. Y., A CORPORATION OF DELAWARE

FORCED-FEED LUBRICATING SYSTEM FOR ROLLER JOURNALS

Application filed February 9, 1928. Serial No. 253,079.

This invention relates to a new and improved forced feed lubricating system for the bearings of the several rollers of a pulverizing mill of the general type shown, for example, in the patent to Raymond et al. 1,573,191, granted February 16, 1926. In a mill of this type, a plurality of pulverizing rollers are pivotally suspended in a circular series from a frame or spider which rotates about a vertical axis, the rollers swinging out by centrifugal force against the inner surface of a fixed circular bull-ring, whereby the material caught between the ring and rollers is pulverized. Means is provided for suspending each individual roller from the spider so that it may rotate about its own axis, and a self-contained lubricating system is usually provided for supplying lubricant to the bearings which rotatably support the roller. According to the present invention, means are provided for forcing lubricant from a source of supply (preferably located outside of the mill) to and through the several bearings of each individual roller, then collecting this oil and returning same to the source.

The principal object of the invention is to provide an improved forced feed lubricating system for a pulverizing mill of this type, as disclosed and claimed hereinafter.

Another object is to provide improved means for distributing lubricant that is forced from a single source of supply, to a plurality of separate roller-lubricating systems, and then collecting the lubricant returned from these separate systems and returning the lubricant to the source.

Another object is to provide improved means for continuously conducting a flow of oil through the several bearings of a single roller assembly.

Other objects and advantages of the invention will be more apparent from the following detailed description of one approved form of the apparatus.

In the accompanying drawings:

Fig. 1 is a central vertical section through the assembled mill and lubricating apparatus.

Fig. 2 is a plan view on a larger scale, of the apparatus shown in Fig. 1, with the cover

of the mill casing and the feeding mechanism, removed.

Fig. 3 is a central vertical section through the oil distributing and collecting head.

Fig. 4 is a horizontal section, taken substantially on the line 4—4 of Fig. 3.

Fig. 5 is a horizontal section taken substantially on the line 5—5 of Fig. 3.

Fig. 6 is a vertical section taken substantially on the line 6—6 of Fig. 3.

Fig. 7 is a vertical section through one of the pulverizing roller assemblies.

Fig. 8 is a horizontal section, on a larger scale, taken substantially on the line 8—8 of Fig. 7.

Fig. 9 is a horizontal section taken substantially on the line 9—9 of Fig. 7.

The invention is here shown as applied to a roller pulverizing mill comprising a base or supporting framework 1 from which rises a central pedestal 2, in which is journaled the main central driven shaft 3. Shaft 3 is rotated by means of a beveled gear 4 fixed to its lower end and meshing with the bevel

pinion 5 on a drive shaft 6. Mounted on the upper end of shaft 3 is the spider or rotating frame 7 from which are suspended the pulverizing rollers indicated generally at 8. In the present example, there are six

of these rollers hung at equally spaced intervals about the periphery of the spider 7 so that they may rotate on their own axes and also swing in vertical planes passing through the axis of the shaft 3. When the assembly is rotated, the rollers swing out-

wardly by centrifugal force against the fixed bull ring 9, the pulverizing rollers 10 rolling along the inner surface of this bull ring to pulverize the material which is introduced by any suitable feeding means such as 11,

mounted in the enclosing housing 12. A rotating skirt or shield 13 is suspended from spider 7 between the rollers and the pedestal 2, and a plurality of plows 14 carried by this

skirt help to feed the material up between the rollers 10 and the bull ring 9 so that it may be pulverized.

There are several approved ways in which the pulverizing rollers may be rotatably suspended from the spider 7, one approved ex-

ample being shown in Figs. 7, 8 and 9, and disclosed more in detail and claimed in applicant's copending application Serial No. 253,080, filed February 9, 1928. Referring 5 now more particularly to Figs. 1, 2, 7, 8 and 9, the spider 7 is formed with a plurality of outwardly projecting yokes 15, in the arms 16 and 17 on each of which is rotatably mounted a trunnion shaft 18. On the trunnion shaft is secured the rocker member 19 having a laterally projecting boss or bracket 20. The roller supporting shaft 21 has an upper conical end portion 22 which is drawn up tightly within the correspondingly shaped 15 opening in boss 20 by means of the nut 23 screwed onto the reduced threaded end portion 24 of the shaft. A key 21^a fitting mating grooves in the boss 20 and shaft 21 prevents relative rotation between these two 20 members.

An oil supply conduit or passage 25 extends axially through shaft 21 from end to end thereof, the upper portion of this passage being enlarged as indicated at 26. A 25 tube 27, of substantially the same bore as the lower portion of passage 25, extends through the enlarged portion 26 so as to divide this passage into a continuation of the supply passage or conduit 25 and an annular outer 30 return passage 28. A cap 29, screwed onto the upper threaded end 24 of shaft 21, is engaged with the upper end of the tube 27 so as to separate the supply and return passages at their upper ends. The trunnion 18 35 is bored out from one end to form an inlet passage 30 and an outlet passage 31. A passage or conduit 32 bored out of the shaft 21, rocker 20 and trunnion 18 connects the annular return passage 28 in the shaft with the 40 outlet passage 31 in the trunnion. A lateral passage 33 extends vertically from the inlet passage 30 through the top of the trunnion and rocker 20, and a screw plug 34 threaded into the top of rocker 20 forms a continuation 45 of this passage. A tubular conduit 35 is connected with plug 34 by means of the cap nut 36 which engages over the enlarged head of tube 35. In an exactly similar manner, the other end of tubular conduit 35 is connected by means of cap 37 and plug 38 with the cap 29 on shaft 21, so that the conduit 35 50 will form a continuation of the tube 27 and supply passage 25 in the shaft 21. A fixture 39 secured to the end of trunnion shaft 18 is 55 formed with two threaded nozzles 40 and 41, conveniently arranged at right angles to one another, whereby flexible conduits 42 and 43 may be connected with the respective inlet and outlet passages 30 and 31, by means of 60 cap nuts 44.

A hollow sleeve or housing 45 surrounds the major portion of shaft 21 concentrically therewith but spaced therefrom as will be hereinafter apparent. A bottom closure 65 member 46 extends around the lower end of

shaft 21, and is removably secured to sleeve or housing 45, the two members being provided with outwardly projecting annular flanges 47 and 48 connected by bolts 49, in the example here shown. The closure member 46 is hollowed out at 50 to form a well for lubricant. The pulverizing roller 10 is clamped to and suspended from the closure member 46, by means of a series of bolts 51.

A nut 52 screwed onto the lower threaded end 53 of shaft 21, supports through washer 54, a sleeve or bushing 55 having an annular ring or nut 56 screwed onto its lower end. Sleeve 55 extends up practically the length of the housing 45 and slidably engages the outer surface of shaft 21 adjacent its upper and lower ends, the shaft 21 being slightly reduced between these points as indicated at 57. Oil passages 58 connect the enclosed annular space 57 with the oil space 59 between the housing 45 and bushing 55. The upper end of bushing or sleeve 55 is flanged outwardly at 60, and a spiral shock-absorbing spring 61 is confined between flange 60 and a fixed annular flange 62 on shaft 21.

A roller thrust-bearing assembly, preferably of the type known as "Bower" roller bearings, supports the sleeve or housing 45 and parts carried thereby from the lower end of shaft 21. The annular series of rollers 63 are confined between an inner race ring 64 which surrounds sleeve 55 and is supported on nut 56, and an outer race ring 65 which fits within an annular recess 66 in the lower end of sleeve 45. A similar roller bearing assembly 67 is provided adjacent the upper end of sleeve 55, the inner race ring 68 being confined beneath the outstanding flange 60 at the upper end of sleeve or bushing 55.

A helical rib or flange 69 projects inwardly from the inner wall of sleeve 45 into rather close proximity to the sleeve 55, although it does not engage therewith. This flange 69 is curved in such a direction with relation to the direction of rotation of the rotating assembly that it will tend to positively lift oil or other lubricant from the well 50 and carry same up through the annular space 59 between the rotating sleeve and the shaft. There is a natural tendency for this oil to travel upwardly, due to the rotation of the container, but the flange 69 forms a means for positively lifting the oil so as to expedite the continuous flow of oil through the rotating assembly.

A cap or closure member 70 is screwed into the upper end of housing 45, above the upper roller bearing 67. Cap 70 has an outstanding flange 71 which extends over the upper end 72 of sleeve 45, flange 71 being provided with a series of recesses 73 adapted to be selectively engaged by the upper end of a locking bar 74 secured to sleeve 45 by screw bolts 75. The elevation of cap 70 may be properly adjusted by screwing the cap into

or out of the sleeve 45, and it is then locked in adjusted position by means of the locking bar 74. The upper end 76 of cap 70 extends into close proximity to an enlarged portion 77 of shaft 21, and houses and supports a pair of annular gaskets 78 and 79 which bear respectively against the shaft 21 and the lower plane face of a collar 80 secured to the shaft. These gaskets are adapted to seal the joint between the shaft and the rotating assembly, and prevent the excessive escape of oil. A very slight escape of oil is desirable in order to combat and prevent the entrance of dust through this joint. The lower face of collar 80 is also provided with a series of partially spiral grooves 81 also tending to work against the escape of oil through this joint.

The walls of the cavity 82 in cap 70 are provided with a spiral rib or flange 83, similar to rib 69 in sleeve 45, for lifting oil through the space within cap 70, above the upper roller bearing 67. Adjacent the upper end of cavity 82, a plurality of radial passages 84 extend inwardly to the annular return passage 28. The inner cylindrical surface of head 76 of cap 70, below the gasket 78, is formed with a helical groove 85 having an inclination opposite to the inclination of ribs 69 and 83, so as to tend to prevent the rise of oil from cavity 82 toward the sealing gaskets 78 and 79.

When in use, this roller will hang freely within the mill and will be permitted to swing freely about the axis of trunnion 18 so that centrifugal force will tend to force the pulverizing roller against the bull-ring. As the supporting spider 7 is rotated, the roller 10 will roll around on the inner surface of the bull-ring 9, whereby the rotatable assembly comprising the roller 10, cap 46, sleeve or housing 45, cap 70, gaskets 78 and 79, and minor features carried by these elements will rotate about the substantially fixed shaft 21. The sleeve or bushing 55 will not ordinarily move, but may be forced upwardly against the shock absorbing spring 61 to take up vertical thrusts, and can if necessary rotate about the shaft 21 in case of injury to the roller bearings, or other binding of parts. Oil or other lubricant is forced in through inlet passage 30, passage 33, and tubular conduit 35, into the upper end of tube 27 and thence down through the supply passage 25 to the lower end of shaft 21 and into the well 50. The rapid rotation of the assembly will tend to throw this oil upwardly through the lower roller bearing and thence upwardly through passage 59 between the rotating sleeve 45 and the shaft. Some of this oil will pass in through openings 58 to the annular space 57 between the bushing 55 and shaft 21. The main volume of the lubricant will be carried upwardly by the helical rib or flange 69, and after passing through the up-

per roller bearing 67 will be carried up by rib 83 and pass out through radial passages 84 to the annular return passage 28, thence through passage 32 to the outlet passage 31 in the trunnion shaft 18. Some of the oil will tend to escape through the joint between cap 70 and the shaft 21 and collar 80, but this escape of oil is largely prohibited by the gaskets 78 and 79, and the oil-returning grooves 81 and 85.

If it becomes necessary to remove or replace the pulverizing roller 10, this may be done by merely removing the bolts 51 without disassembling the remainder of the rotating assembly.

The specific form of pulverizing roller assembly just described, is disclosed and claimed in my copending application, Serial No. 253,080. The present invention relates particularly to mechanism cooperating with a series of rollers of this general type for supplying a continuous flow of lubricant under pressure to and through the bearings of the several individual rollers. While the roller assembly just described is especially adaptable for use in such a lubricating system, the lubricating system now to be described could be used with other forms of roller-assemblies, it only being necessary that provision be made within the roller-supporting means for permitting a continuous flow of oil through the bearings.

A base or standard 86 is mounted centrally on spider 7 above the end of driven shaft 3, and this base or standard supports the distributing and collecting head now to be described, and best shown in Figs. 3 to 6 inclusive. This head comprises a bottom plate 87 and a hollow casting 88, provided with a central web 89 which divides the head into a lower distributing chamber 90, and an upper collecting chamber 91. A series of spaced outlet openings 92 are formed around the periphery of chamber 90, in each of which is positioned an outlet plug 93. The inner ends of the several flexible conduits 42, which lead to the different roller-assemblies, are connected in communication with distributing chamber 90 by means of screw caps 94 secured on the outer ends of the several screw plugs 93. In an exactly similar manner, the collecting chamber 91 is provided with a plurality of inlet openings 95 in which are positioned screw plugs 96. The flexible conduits 43 through which lubricant is returned from the roller assemblies have their inner ends connected in communication with collecting chamber 91 by means of screw caps 97 threaded onto the plugs 96.

A tubular member 98 is supported in vertical position coaxially with the driven shaft 3, by means of an outwardly projecting flange 99 in its upper end which is bolted at 100 to a supporting ring 101 carried by a plurality of radial arms or struts 102 secured at their

70

75

80

85

120

125

130

outer ends to the housing 12 of the mill. The lower end of tubular member 98 projects downwardly through the distributing and collecting head, so that the head may rotate 5 about it as an axis. The lower end 103 of tubular member 98 is journaled in a bushing 104 mounted in a hub 105 formed centrally in the bottom plate 87 of the head. A plurality of circumferentially arranged openings 106 place the interior of tubular member 98 10 in communication with the distributing chamber 90. The intermediate portion of member 98 is journaled in the web 89 and also in the gland 107 adjustably mounted in the web and adapted to force a packing 108 15 into engagement with tubular member 98 in order to seal the joints around the tubular member between the chambers 90 and 91. Above the web 89, the member 98 is formed 20 with an inner annular web 109 connected at its upper and lower ends to the outer wall of member 98 so as to separate the annular chamber 110 from the main passage 111 extending through member 98. A circumferential series of openings 112 connects the 25 annular chamber 110 with the collecting chamber 91 in the head. The upper portion of member 98 is journaled in a bushing 113 mounted in the upper hub 114 of the head, and a gland 115 adjustably mounted in the 30 upper end of the head is adapted to force a gasket 116 into sealing engagement with the tubular member 98. A fixture 117 secured to the upper end of member 98, is connected by a 35 screw cap 118 with the oil supply pipe 119. A nozzle 120 is formed on one side of the upper end portion of member 98, in communication with the annular chamber 110 in this member, the nozzle being connected by a 40 screw cap 121 with the outlet pipe 122.

The supply pipe 119 and return pipe 122 extend out through one side of the mill housing and communicate with any suitable and well known form of oil-filter or oil purifier, reservoir and pumping system by means of which 45 a continuous supply of oil may be forced in through pipe 119 and drawn out through pipe 122.

In operation, oil will flow in through pipe 50 119, passage 111 in tubular member 98, and outlet ports 106 into the distributing chamber 90. From this chamber oil will flow through the several outlet passages 92 and flexible conduits 42 to the various roller assemblies, through which the oil will flow in 55 the manner described hereinabove. The oil will return from the roller assemblies through the several flexible conduits 43 and be discharged into the collecting chamber 91, from which it will flow out through 60 passages 112 into the annular chamber 110 in stationary tubular member 98, from which it is withdrawn through nozzle 120 and return pipe 122, and thence back to the oil filter and pumping system. It will be apparent that 65

this system is entirely automatic, and that a continuous flow of oil is provided through all of the roller assemblies, even though these rollers are completely housed within the mill and are given a continuous planetary motion about the axis of the rotating spider. 70 The oil supply and pumping system are stationary and may be positioned at any convenient location outside of the mill.

I claim:

1. In a pulverizing mill, the combination 75 with a frame rotating about a vertical axis, a bull-ring, a plurality of pulverizing rollers suspended from said frame so that they may swing out by centrifugal force against the bull-ring, and means comprising a plurality of bearings for rotatably supporting each roller from the frame, of means for causing a continuous flow of oil from a central source through the bearings of the several rollers and back to the source. 80

2. In a pulverizing mill, the combination 85 with a frame rotating about a vertical axis, a bull-ring, a plurality of pulverizing rollers suspended from said frame so that they may swing out by centrifugal force against the bull-ring, and means comprising a plurality of bearings for rotatably supporting each roller from the frame, of means for causing a continuous flow of oil from a central source 90 through the bearings of the several rollers and collecting and withdrawing the oil discharged from the bearings. 95

3. In a pulverizing mill, the combination 100 with a frame rotating about a vertical axis, a bull-ring, a plurality of pulverizing rollers suspended from said frame so that they may swing out by centrifugal force against the bull-ring, and means comprising a plurality of bearings for rotatably supporting each 105 roller from the frame, of means for causing a continuous flow of oil to and from a source of supply outside of the mill, and means within the mill for dividing this oil flow into a plurality of separate streams, one of which passes through the bearings of each roller. 110

4. In a pulverizing mill, the combination 115 with a frame rotating about a vertical axis, a bull-ring, a plurality of pulverizing rollers suspended from said frame so that they may swing out by centrifugal force against the bull-ring, and means comprising a plurality of bearings for rotatably supporting each roller from the frame, of an oil distributing and collecting mechanism mounted in line 120 with the axis of rotation, means for conducting oil to and from this distributor from an outside source of supply, and means for conducting oil from the distributor to the bearings of each roller and back to the distributor. 125

5. In a pulverizing mill, the combination 130 with a frame rotating about a vertical axis, a bull-ring, a plurality of pulverizing rollers suspended from said frame so that they may swing out by centrifugal force against the

- bull-ring, and means comprising a plurality of bearings for rotatably supporting each roller from the frame, of a head mounted on the frame in line with the axis of rotation and formed with separate collecting and distributing chambers, a non-rotatable tubular member positioned coaxially with the frame and projecting through the chambers, separate passages in said tubular member one of which has ports communicating with the distributing chamber and the other having ports communicating with the collecting chamber, a pair of conduits leading from the passages in the tubular member to a source of oil supply, and a pair of conduits for each roller assembly, one conduit leading from the distributing chamber to the roller and the other leading from the roller back to the collecting chamber. 70
6. In a pulverizing mill, the combination with a frame rotating about a vertical axis, a bull-ring, a plurality of pulverizing rollers suspended from said frame so that they may swing out by centrifugal force against the bull-ring, and means comprising a plurality of bearing for rotatably supporting each roller from the frame, of a head mounted on the frame in line with the axis of rotation and formed with separate collecting and distributing chambers, a non-rotatable tubular member positioned coaxially with the frame and projecting through the chambers, separate passages in said tubular member one of which has ports communicating with the distributing chamber and the other having ports communicating with the collecting chamber, a pair of conduits leading from the passages in the tubular member to a source of oil supply, each roller assembly being formed with passages for conducting lubricant to and through the several bearings, and a pair of conduits for each roller connecting the inlet and outlet of these passages with the distributing and collecting chambers respectively. 80
7. In a forced feed lubricating system for the rollers of a pulverizing mill, in combination with the rotating spider and the several roller-assemblies carried thereby, a distributing head mounted coaxially with the spider and comprising a housing secured to the spider and rotating therewith and formed with a distributing chamber, a non-rotary tubular member journaled centrally within the housing and formed with passages communicating with the chamber, conduits connecting the distributing chamber with the several roller-assemblies, and a conduit for feeding oil to the tubular member. 90
8. In a forced feed lubricating system for the rollers of a pulverizing mill, in combination with the rotating spider and the several roller-assemblies carried thereby, a distributing head mounted coaxially with the spider and comprising a housing secured to
- the spider and rotating therewith and formed with separate distributing and collecting chambers, a non-rotary tubular member journaled within the housing and formed with separated interior feed and return passages, ports connecting these passages with the distributing and collecting chambers respectively, a pair of conduits connecting each roller assembly with the two chambers, and supply and return conduits communicating with the feed and return passages in the tubular member. 95
9. In a forced feed lubricating system for the rollers of a pulverizing mill, in combination with the rotating spider and the several roller-assemblies carried thereby, a distributing head mounted coaxially with the spider and comprising a housing secured to the spider and rotating therewith and formed with separate distributing and collecting chambers, a non-rotary tubular member journaled within the housing and projecting through both chambers and formed with separated interior feed and return passages, sealing means surrounding the tubular member between the chambers and where the tubular member emerges from the housing, there being ports in the tubular member connecting the feed and return passages therein with the distributing and collecting chambers respectively, a series of conduits leading from the distributing chamber to the several roller assemblies, and another series of conduits leading from the roller assemblies back to the collecting chamber, and supply and return pipes communicating with the feed and return passages in the tubular member. 100
